APPARATUS FOR OPENING A BOBBY PIN

Leida M. Apri and Eduard V. Apri, Altadena, Calif., assignors to Rexall Drug and Chemical Company, Los Angeles, Calif., a corporation of Delaware

Filed Mar. 12, 1962, Ser. No. 178,967

1 Claim. (Cl. 132—1)

This invention relates to bobby pin openers. More particularly, it relates to bobby pin openers wherein the bobby pin is retained in an opened condition on the opener.

A bobby pin is commonly known as that type of hair clip which is fabricated from a unitary length of spring metal. The spring metal is bent into a U-shape wherein the legs of the U lie closely adjacent one another. Conventionally, the extent of one of the legs is formed into a series of convolutions lying adjacent the other of the legs. Normally, the unconvoluted leg of the pin extends beyond the convoluted leg. The portion of the convoluted leg immediately adjacent the free or cantilevered end of such leg extends at an angle away from the longer straight leg of the pin. Such a pin is normally utilized to retain selected portions of a woman's hair in place relative to a fashionable hair arrangement.

When such pins are used, it is most generally the case that the woman uses one hand to retain in place the selected lock of hair to be pinned. The other hand must accomplish the process of selecting a bobby pin from a supply thereof and opening the bobby pin for engagement with the selected lock held by the other hand. The spring engagement between the substantially parallel legs of the bobby pin, however, makes it difficult for a bobby pin to be opened easily and swiftly with only one hand.

It is quite common for a woman using a bobby pin to either force the ends open by engaging a fingernail between the opposite cantilevered ends of the pin, or to utilize the mouth to engage the longer end of the pin while pulling the convoluted leg outwardly against the action of the resilient return bend joining the legs. The first of these two methods often results in broken fingernails and cut fingers, especially when the ends of the bobby pin are not protected by a resilient cushion as is frequently the case. The second of these two methods, is an unsanitary method and is damaging to the teeth.

This invention provides an apparatus with which a bobby pin may be engaged for opening of the bobby pin. The invention provides a device wherein the bobby pin, after being opened, may be left engaged with the device; the pin will remain in an opened condition for subsequent engagement by the user. This second feature of the invention provides that if a last minute adjustment in the arrangement of the hair is required—such an adjustment frequently requiring the use of two hands, a bobby pin previously opened need not be returned to its supply but may be retained in a condition for immediate use in clipping the hair in place. These features are provided in an apparatus which is simple, safe, inexpensive, and effective.

Generally speaking, the bobby pin opener and holder of the invention comprises a block of material defining a planar surface. A second surface intersecting the planar surface at an acute angle, and extending downwardly obliquely from the first surface, is defined by the block. The second surface curves away from the intersection with the first surface to an edge spaced apart from the intersection, the edge being oriented substantially perpendicularly to the planar surface. The block also includes a third surface which is spaced from and connected to the first and second surfaces by connector bars extending between and joined to the surfaces. The third

2

surface is plane and forms an extension of the second surface a sufficient distance to provide a slot between the second and third surfaces along the intersecting line between the first and second surfaces. The slot is sufficiently wide between the second and third surfaces to admit only one leg of a bobby pin. The bobby pin is opened by the user grasping the pin, engaging and sliding the free end of a first pin leg along the third surface until this leg enters the slot and engages the first surface and the second pin leg engages the second surface, and the pin is pushed downwardly on the pin connector to resiliently spread the legs of the pin apart by the first pin leg sliding downwardly along the first surface and the second leg sliding downwardly along the second surface. When the pin has been moved relative to the block such that one of the zig-zag configurations of the pin is engageable with the edge, the pin is retained on the block with the leg of the pin spaced apart. In this condition, the force causing engagement between the pin and the block may be removed and the pin will be retained in an opened condition upon the block with the legs of the pin being engaged against the edge and the planar surface of the block.

The invention also includes the combination of a bobby pin opener and holder with a dispenser for bobby pins. The dispenser dispenses a single bobby pin upon each operation of the dispenser. The pin is dispensed in a manner so as to be readily engageable in one hand operation with the opener, the opener serving to open the dispensed pin and to retain the opened pin thereon.

The above mentioned and other features and object of this invention are more fully set forth in the following detailed description taken in conjunction with the accompanying drawings wherein:

FIGURE 1 is an elevational view of the opener of this invention, illustrating a bobby pin dispenser in cross section;

FIGURE 2 is an enlarged cross-sectional view of the bobby pin opener block as taken along line II—II of FIGURE 1; and

FIGURE 3 is an elevational view of a bobby pin.

Referring to FIGURE 1, the bobby pin opener 10 is illustrated mounted to a planar base or mounting plate 11. The opener 10 comprises a block 12 of material defining a planar face 14. In a preferred form of the invention, the block 12 is fabricated from a rigid material such as plastic, and the planar face 14 is oriented vertically with respect to an upper surface 15 of the mounting base 11.

The block 12 defines a second surface 16 intersecting the first surface 14 at an acute angle intersection 17. Preferably, the second surface 16 is defined by the upper surface of the block 12 and curves concavely upwardly away from intersection 17 to an edge 19 spaced apart from intersection 17. Edge 19 preferably lies parallel to first planar surface 14. A portion 18 of surface 16 adjacent to edge 19 preferably lies substantially perpendicular to first surface 14.

To facilitate further description of the opener 10, reference is had to a bobby pin 20 illustrated in FIGURE 3. The bobby pin is normally fabricated from a length of narrow strip of material, usually metal, having suitable resilient characteristics. The strip is formed into a U-shaped configuration having a pair of legs 21 and 22 joined by a return bend portion 23. One leg 21 is formed into a zig-zag configuration with a portion 25 immediately adjacent the free or cantilevered end 26 thereof extending away from the end portion 27 of the other leg 22. In the conventional bobby pin, the distance between the return bend portion 23 and the free end 26 of the figure leg 21 is less than the length of leg 22 from bend 23 to end 28. The ends 26 and 28 of legs 21 and

are normally covered with a bulb or cushioned bead of rubber or plastic material to blunt the respective ends of the legs of the bobby pin 20 to prevent severing strands of hair and to prevent scratching or gouging the scalp of the user of the bobby pin. This bulb further provides an enlargement which further serves to maintain the bobby pin in open condition upon opener 10 through frictional engagement with said opener 10 as will hereinafter become more obvious.

As illustrated in FIGURE 3, the end portions 25 and 26 of legs 21 and 22, respectively, lie at an acute angle relative to one another and they diverge relative to each other toward the ends 26 and 28 of the respective legs. The angular relation defined between first surface 14 and second surface 16 on block 12 adjacent intersection 17 is an acute angle of a larger magnitude than the angle between the end portions 25 and 27 of bobby pin 20. In operation of the opener 10, a bobby pin 20 is initially positioned in engagement with the block 10 so that the end 26 of leg 21 engages the concave upwardly second surface 16 while the end 28 of leg 22 engages the first planar surface 14 adjacent intersection 17 of block 12. The user of the bobby pin then forces the return bend portion 23 of pin 20 toward intersection edge 17. Such engagement causes the leg end 26 to move along surface 16 away from intersection 17 as the substantially straight leg 22 of pin 20 moves downwardly along surface 14. The application of engaging force between pin 20 and block 12 is continued and such motion continues until end 26 of the figured leg 21 of pin 20 passes over edge 19 of the second surface 16. At this point edge 19 engages within a convolution or zig-zag configuration 32 of the shorter leg 21. Most generally the edge 19 is engaged within the zig-zag convolution 32 closest to the end portion 25 of leg 21 since the portion 18 of surface 16 adjacent edge 19 lies substantially perpendicular to surface 14. This engagement is sufficient to cause frictional retention between leg 21 and edge 19. This retention, and also the frictional engagement between leg 22 and surface 14, is sufficient to maintain the bobby pin 20 upon block 12 in an open condition.

To facilitate increased frictional engagement between leg 22 and first planar surface 14 of block 12, a plurality of raised ribs 35 are provided in the first surface 14. These ribs 35 are disposed parallel to intersection 17. Engagement between the bulb or cushioned bead 30 of leg 22 with one of the ribs 35 increases the frictional engagement between the bobby pin and the block and thereby further serves to retain the pin 20 upon block 12. Furthermore, a preferred opener 10 includes an insert of soft plastic or rubber mounted so as to define edge 19 of surface 16, this insert 36 deforms when engaged with convolution 32 and provides further increased frictional retention of pin 20.

An extension portion 40 of second surface 16 is provided on block 12 so as to define a third surface. This third surface 40 is spaced from intersection 17 to define an opening 41 relative to the intersection 17. As illustrated in FIGURE 2, surface 40 is convex upwardly. The surface 40 is defined by a horizontal web or rib 42 situated between a pair of brackets 43 extending from the edges of the block 12 defining the first planar surface 14.

The surface 40 aids in properly locating end 28 of the longer leg 22 of pin 20 relative to the intersection 17 and to first surface of block 12. The width of opening 41 along the extent of surface 16 is insufficient to permit both ends 26 and 28 of pin 20 to pass therethrough, which results in end 26 being engaged with surface 16 for movement therealong toward edge 19.

To further facilitate proper orientation of the bobby pin 20 relative to block 12, a rib 45 is formed in block 12 along each of the opposite edges of surface 16. Each rib 45 extends from edge 19 to the remote limit of the third surface 40. Preferably the ribs 45 are parallel to one another.

As illustrated in FIGURE 2, the preferred form of the block 12 defines an internal cavity 46 opening downwardly of the block 12. Block 12 preferably is mounted to base 11 by engagement with a mounting block 47 secured to the upper surface 15 of base 11 and engaged within the cavity 46.

To further facilitate speedy and convenient use of the opener 10, this invention includes a dispenser 50 for bobby pins mounted to base 11 adjacent the bobby pin opener 10. The dispenser 50 is fabricated from a pair of relatively reciprocable sleeves 51 and 52. Sleeve 51 is mounted to the upper surface 15 of base 11 and defines an axial bore 53. The upper end of sleeve 51 defines an inwardly extending annular flange 55.

The upper reciprocatory sleeve 52 defines a bobby pin receptacle and has an external diameter smaller than the internal diameter defined by flange 55 of sleeve 51. Cylinder 52 has an outer peripheral flange 57 adjacent its lower end engaged within bore 53 of sleeve 51 and abuttable against flange 55. The lower end of sleeve 52 is closed by a bottom part 58 configured concave upwardly of sleeve 52. An aperture 59 is formed centrally of the bottom 58 of sleeve 52. A cap member 61 is engaged with the upper end 62 of sleeve 52. The cap member 61 has a recess 63 in its under surface 64, which recess has a concave downwardly configuration. An aperture 65 is formed axially of cap 61 in communication with the uppermost limit of recess 64.

A pedestal member 68 is mounted coaxially of cylinders 51 and 52 and is secured in a rigid manner relative to the mounting base 11. Pedestal 68 is disposed so as to project through aperture 59 in the bottom 58 of cylinder 52. In the preferred form of the invention, pedestal 68 has a concave recess formed in its upper end. A coil spring 30 is mounted within the bore 53 of cylinder 51 and bears against the lower side of sleeve 52 to urge sleeve 52 upwardly of cylinder 51 so that flanges 57 and 55 are normally engaged.

A cavity 75 is defined within the upper reciprocatory cylinder 52. This cavity 75, in conjunction with the apparatus described above, has concave opposite ends. The cap 61 is removable from sleeve 52 so that a plurality of bobby pins 20 may be disposed within cavity 75. Preferably the bobby pins 20 are disposed in cavity 75 with the return bend portions 23 oriented upwardly of cylinder 52.

To operate the dispenser 50, the upper cylinder 52 is depressed downwardly against the action of the spring 70 so that the pedestal 68 then protrudes upwardly through aperture 59. As pedestal 68 emerges through aperture 59 it randomly selects one of the lower ends 28 of bobby pin 20 forcing that particular bobby pin upwardly relative to the cavity 75. The concave downwardly configuration of recess 64 in cap 61 forces the return bend portion 23 of the selected bobby pin centrally of the cap 61 toward aperture 65. As depression of cylinder 52 relative to sleeve 51 continues, the upper end of the selected bobby pin emerges through aperture 65 to be grasped by the operator of the dispenser. The pedestal member 68 and spring 70 comprise means operatively connected to the receptacle 52 to project the return bend portion 23 of a selected pin 20 from the receptacle upon each operation of the dispenser 50.

In conjunction with the bobby pin opener 10, the dispenser 50 has particular utility since the dispenser may be operated with only one hand. This novel combination of apparatus allows a woman preparing a fashionable hair arrangement to keep one hand in contact with the particular lock of hair under treatment, thus leaving the other hand free to operate the dispenser 50. This free hand then can grasp the randomly selected bobby pin emerging from dispenser 50 and open it through the use of the opener 10.

As may be observed from the foregoing description, this invention provides apparatus for quick and simple

selection of a bobby pin from a supply of bobby pins and for effective and simple opening of the bobby pin. The apparatus further provides a means whereby the bobby pins, after having been opened, may be retained in an open condition on the device utilized for opening the pins.

While the invention has been described above in conjunction with specific apparatus, this has been by way of example and is not to be considered as limiting to the scope of this invention.

We claim:

An opener and holder for a bobby pin having first and second similar parallel legs joined at one end by a resilient connector to maintain the legs resiliently together and having free ends movable apart relative to each other, said opener and holder comprising a block of material having a first vertically extending substantially plane surface and a second surface extending downwardly obliquely from the first surface; said surfaces intersecting along a horizontal line at an acute angle to each other; said second surface being continuous, concave and extending to an outer edge spaced from and substantially parallel to said horizontal intersecting line; a third surface spaced from and connected to the first and second surfaces, said third surface being connected to the first and second surfaces by connector bars extending between

and joined to the surfaces, said third surface being planar and forming an extension of said second surface laterally spaced from the second surface a sufficient distance to provide a slot between the second and third surfaces along said horizontal intersecting line of the first and second surfaces, said slot being sufficiently wide between the second and third surfaces to admit only one leg of the bobby pin, said bobby pin being opened and held by the user grasping the connector of the pin, engaging a 10 slot the free end of the first pin leg along the third surface until the last mentioned pin leg enters said slot and engages the first surface and the second pin leg engages the second surface, and then pushing downwardly on the pin connector to resiliently spread the legs apart by the first pin leg sliding downwardly along the first surface and the second leg sliding downwardly along the second surface.
